UNITED STATES PATENT OFFICE.

ULYSSES D. EDDY, OF NEW YORK, N. Y.

DESIGN FOR COFFEE-POT STAND.

Specification forming part of Design No. **11,423**, dated September 23, 1879; application filed July 19, 1879.
[Term of patent 3½ years.]

To all whom it may concern:

Be it known that I, ULYSSES D. EDDY, of New York city, in the county of New York and State of New York, have invented a new Design for Coffee-Pot Stands; and I do hereby declare the following, when taken in connection with the accompanying drawing and the letters of reference marked thereon, to be a full, clear, and exact description of the same, and which said drawing constitutes part of this specification, and represents a top view of a stand embodying my design.

This invention relates to a design for the article known as a "coffee-pot stand"—that is, a metal stand to be placed upon the table on which to set tea or coffee pots, and for similar uses; and the invention consists in the shape and ornamentation, as hereinafter described, and shown in the accompanying illustration.

The stand is in shape of a horseshoe, and in the center is the representation of a horse's head surrounded by a motto; but the motto may be omitted, or other ornamentation may be substituted for it, the essential feature of the design being the horseshoe-shaped frame with the horse's head in the center.

I claim—

The design for a coffee-pot stand, consisting of the horseshoe-shaped frame with representation of a horse's head in the center, as shown and described.

ULYSSES D. EDDY.
